(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outer broken lines in the figure show a display or portion thereof, and form no part of the claimed design. The other broken lines in the FIGURE show portions of the graphical user interface or animated graphical user interface that form no part of the claimed design.

UNITED STATES PATENT AND TRADEMARK OFFICE
CERTIFICATE OF CORRECTION

PATENT NO. : D993,975 S
APPLICATION NO. : 29/845820
DATED : August 1, 2023
INVENTOR(S) : Chen et al.

Page 1 of 1

It is certified that error appears in the above-identified patent and that said Letters Patent is hereby corrected as shown below:

On the Title Page

In the Description section, please replace the following statement:

“The outer broken lines in the figure show a display or portion thereof, and form no part of the claimed design. The other broken lines in the FIGURE show portions of the graphical user interface or animated graphical user interface that form no part of the claimed design.”

With:

--The outer broken lines in the FIGURE show a display screen or portion thereof, and form no part of the claimed design. The other broken lines in the FIGURE show portions of the graphical user interface that form no part of the claimed design.--
